UNITED STATES PATENT OFFICE

GEORGE F. LINDSLEY, OF WAUWATOSA, WISCONSIN

BASE BLOCK

Application filed May 3, 1930. Serial No. 449,534.

This invention relates to new and useful improvements in base blocks for tile walls, and the like.

In the construction of tile walls, it is necessary to provide anchor strips in the wall as it is built up for attaching the baseboard, molding and other wooden parts to the wall, and it has been found rather difficult to properly secure anchor strips to a tile wall in such manner that they will be securely retained in position so that the molding, baseboard and other wooden strips can be attached thereto.

It is one of the objects of this invention to provide a base or anchor block which will have embedded therein connecting pieces, whereby anchor strips can be attached thereto and which will be so positioned with respect to the plaster arranged over the usual tile wall, that the outer faces of these anchor strips will be flush with the plaster and will provide suitable means for attaching molding, baseboards and the like to the tile wall.

Another object of the invention is the provision of a base block for tile walls wherein transversely disposed wooden pieces are embedded in the block during the making thereof, so that anchor strips can be attached to opposite sides of the block, and when in this position, will have a tendency to cooperate with each other and prevent any lateral movement on the part of the strips embedded in the block, the anchor strips providing sufficient means whereby the baseboard, molding or other wooden parts can be attached to the tile wall.

With the above and other objects in view, the invention consists in the novel features of construction, the combination and arrangement of parts hereinafter more fully set forth, pointed out in the claim and shown in the accompanying drawing wherein:

Figure 1 is a perspective view illustrating the construction and application of my improved base block; and,

Figure 2 is a detailed vertical section on the line 2-2 of Figure 1.

Referring more particularly to the drawing, 1 indicates the usual type of construction tile for providing tile walls in build-

ings, for dividing the interior of the building into rooms. Upon one face of the tile is the usual plaster 2 and due to this type of construction, it has been found rather difficult to properly position anchor strips with respect to the wall whereby the baseboard, molding or other wooden articles, can be attached in proper position.

In the present form of the invention, I provide a plastic block generally indicated at 3 having spaced openings 4 therethrough and adjacent each end of the block, I provide two connecting blocks 6 and 6', the block 6 being positioned within the plastic block 3 at a point adjacent one side thereof, with each end of the block 6 flush with opposed side walls of the plastic block. Directly below the block 6 is the second block 6' which extends transversely through the plastic block with its ends flush with the side walls. The two sets of blocks are carried by the plastic block with one set arranged at each end and attached to these anchor blocks are the anchor strips 7 and 7', the anchor strips 7 being nailed or otherwise connected to the ends of the blocks 6, as shown in Figure 2, while the strips 7' are nailed or otherwise secured to the ends of the connecting blocks 6'.

As shown in Figure 1, the anchor strips 7 and 7' are so positioned with the baseboard 8 that it can be easily attached to the wall in its proper position. However, it will be understood that in building up a tile wall, these anchor blocks 3 can be arranged between the tile at any position desired so that should it be necessary to attach a molding to the wall at a height of three, four, or five feet, a series of anchor blocks can be positioned within the wall so that the anchor strips will be in suitable position for attaching the molding thereto.

In fact these base blocks 3 can be fitted into the wall in any desired position whenever an anchor strip is desired to attach molding or other articles thereto. Heretofore, it has been found rather difficult to attach anchor strips to tile walls, but by constructing a base block such as illustrated with transverse blocks embedded therein, to which the anchor strips are secured, it will pro-

vide efficient means for positioning anchor strips in tile walls. Attention is directed to the fact that these anchor strips are preferably of a thickness equal to the usual coating of plaster applied to the walls, so that the outer face of the anchor strips will lie substantially flush with the outer face of the plaster when applied to the wall, thus providing a comparatively smooth finish to the wall with the anchor strips embedded therein.

It will be apparent from the foregoing that I have provided a very simple and inexpensive anchor block for tile walls, whereby suitable wooden anchor strips can be fitted within the wall wherever required, and by having the strips 7 and 7' positioned upon opposite sides of the wall, the connecting blocks 6 and 6' will be securely held in proper position with respect to the plastic blocks, and will also retain the anchor strips in proper position, so that molding, baseboards, or the like can be attached thereto.

Attention is directed to the fact that a number of the plastic blocks may be arranged in alignment and the connecting strips 7 and 7' can be long enough to include several of the blocks so as to connect them to form a unit.

The device is very simple in construction

and it can be manufactured at a very low cost, and at the same time will prove very efficient and desirable in the construction of tile walls.

While I have shown and described the preferred embodiment of my invention, it will be apparent from the foregoing that slight changes may be made in the construction when putting the invention into practice without departing from the spirit of the same or the scope of the appended claim.

I claim:

A wall block comprising a body formed of plastic material, transversely extending anchor blocks embedded in the body and arranged in spaced relation, one of said anchor blocks being embedded in one face of the body with one edge flush with said face, the other anchor block being embedded in the body adjacent the opposite face, the ends of both of the anchor blocks lying flush with the opposite sides of the body, and longitudinally extending parallel wooden strips on opposite faces of the body and secured to the ends of the embedded anchor blocks.

In testimony that I claim the foregoing I have hereunto set my hand at Milwaukee, in the county of Milwaukee and State of Wisconsin.

GEORGE F. LINDSLEY.
